WIRELESS RECEIVING STATIC ELIMINATOR

Filed June 26, 1930

INVENTOR:

Alexander Graham Anderson

UNITED STATES PATENT OFFICE

ALEXANDER GRAHAM ANDERSON, OF WHITELAND, INDIANA

WIRELESS RECEIVING STATIC ELIMINATOR

Application filed June 26, 1930. Serial No. 463,950.

My invention relates to the elimination or reduction of static, station interference, and any other electrical interference due to alternating or varying electric current or voltage, 5 and employs the following means.

1. Two balancing circuits associated with a signal-receiving circuit; one of said balancing circuits being tuned to receive frequencies slightly lower than the desired signal-frequency; and the other of said balancing circuits being tuned to receive frequencies slightly higher than the desired signal-frequency.

2. A four-circuit inductor for separating static from the desired signal. This four-circuit inductor, to be known as the first inductor, consists of a primary, two closely-coupled secondaries, and a loosely-coupled secondary. The primary performs the usual primary function of receiving the varying electric energy and converting it into an electromagnetic field, in which magnetic field the damped static energy remains relatively close to the primary, and the undamped signal energy reaches out beyond the static energy. The two closely-coupled secondaries occupy the portion of the magnetic field where the static is, and the loosely-coupled secondary occupies the portion of the magnetic field where the signal energy reaches.

3. A four-circuit inductor for neutralizing the static component of electric energy associated with the signal. This four-circuit inductor, to be known as the second inductor, 35 consists of three primaries and a secondary. Two of these primaries are connected thru the two tuned balancing circuits to the two closely-coupled secondaries of the first inductor and receive the separated static component. The third primary of this second inductor is in opposite phase to its other two primaries and connects thru the tuned signal-circuit to the loosely-coupled secondary of the first inductor and receives the signal energy. The secondary of this second inductor connects with the receiver. All the primaries of the two inductors are preferably grounded.

50 The electric process which takes place is as follows. Due to the tuning of the three

circuits the greater part of the signal energy goes thru the signal circuit, because the signal-circuit is tuned for the signal-frequency, and the two balancing circuits are tuned, one above and the other below, the signal-frequency. All three circuits receive a part of the static energy, but because the secondaries of the two balancing circuits occupy the portion of the magnetic field where the static prevails, the static energy is partial to the 55 two balancing circuits, while the signal energy is partial to the signal-circuit. By tuning the two balancing circuits correctly the two together will receive the same amount of static energy as goes thru the signal-circuit, 60 while the greater part of the signal energy will go thru the signal-circuit. The static component that goes thru the two balancing circuits and the static component that goes thru the signal-circuit are received by the three primaries of the second inductor and neutralize each other. The signal energy also suffers to some extent from this neutralizing process, but since only a small part of the signal energy goes thru the balancing circuits, the signal energy is only slightly neutralized. The secondary of the second inductor picks up the static-free component of signal energy that remains after the neutralizing process, and carries it to the receiver. For best results these two four-circuit inductors should be shielded with grounded shields, as this prevents picking up fresh static from the atmosphere.

75 The accompanying drawing illustrates the use of my invention between the antenna and the input circuit of a receiver, but the invention may be used between the adjacent parts of any signal-bearing circuit.

80 The inductors shown in the accompanying drawing are of the coil type, but any type of suitable inductors may be used.

85 In the accompanying drawing, A represents the antenna, R the receiver, P the primary of the first inductor, S the loosely-coupled signal-receiving secondary of the first inductor, S₁ the closely-coupled secondary of the first inductor for receiving low-frequency static, S₂ the closely-coupled secondary of the first inductor for receiving 90 95 100

high-frequency static, P' the primary of the second inductor for receiving signal energy, P_1 the primary of the second inductor for receiving low-frequency static, P_2 the primary of the second inductor for receiving 5 high-frequency static, S' the signal-receiving secondary of the second inductor, K the tuning condenser for the signal-circuit, K_1 the tuning condenser for the low-frequency balancing circuit, K_2 the tuning condenser for 10 the high-frequency balancing circuit, G the ground for primary P , G' the ground for primary P' , G_1 the ground for primary P_1 , G_2 the ground for primary P_2 .

15 I claim:

1. A static and interference eliminator, adapted for connection between the antenna and input circuit of a receiver, which consists of two four-circuit inductors coupled by two 20 balancing circuits and a single-circuit; the first four-circuit inductor consisting of a primary, two closely-coupled secondaries and a loosely-coupled secondary, and the second four-circuit inductor consisting of three 25 primaries and a secondary; the two closely-coupled secondaries of the first four-circuit inductor being parts of balancing circuits, one tuned slightly above and the other slightly below the receiver tuning, and the loosely- 30 coupled secondary of the first four-circuit inductor being a part of the signal circuit tuned with the receiver; the two closely-coupled balancing secondaries of the first four-circuit inductor being connected thru tuning 35 condensers to two of the primaries of the second four-circuit inductor which two primaries are in opposite phase to the third primary of the second four-circuit inductor; the loosely-coupled signal receiving second- 40 ary of the first four-circuit inductor being connected thru a tuning condenser to the third primary of the second four-circuit inductor; the primary of the first four-circuit inductor being connected with the antenna, 45 and the secondary of the second four-circuit inductor being connected with the receiver; all of the primaries being grounded.

2. A static and interference eliminator, adapted for connection between adjacent 50 parts of a signal-bearing circuit, which consists of two four-circuit inductors coupled by two balancing circuits and a signal-circuit; the first four-circuit inductor consisting of a primary, two closely-coupled secondaries and 55 a loosely-coupled secondary, and the second four-circuit inductor consisting of three primaries and a secondary; the two closely-coupled secondaries of the first four-circuit inductor being parts of the balancing circuits, 60 one tuned slightly above and the other slightly below the receiver tuning, and the loosely-coupled secondary of the first four-circuit inductor being a part of the signal circuit tuned with the receiver; the two closely-coupled 65 balancing secondaries of the first four-

circuit inductor being connected thru tuning condensers to two of the primaries of the second four-circuit inductor which two primaries are in opposite phase to the third primary of the secondary four-circuit inductor; the loosely-coupled signal-receiving secondary of the first four-circuit inductor being connected thru a tuning condenser to the third primary of the second four-circuit inductor; the primary of the first four-circuit inductor being connected electrically with the preceding part of the adjacent signal-bearing circuit, and the secondary of the second four-circuit inductor being connected electrically with the succeeding part of the adjacent signal-bearing circuit.

3. A static and interference eliminator, adapted for connection between adjacent parts of a signal-bearing circuit; which consists of two multi-circuit inductors coupled by a signal circuit and one or more balancing circuits; the first multi-circuit inductor consisting of a primary a signal-receiving secondary and one or more static-receiving secondaries coupled in the prevailing static-portion of the primary's field; the second multi-circuit inductor consisting of a normal-phase primary and one or more opposite-phase primaries and a secondary; the signal-receiving secondary of the first multi-circuit inductor and the normal-phase primary of the second multi-circuit inductor being parts of the signal circuit tuned with the receiver; the static-receiving secondary or secondaries of the first multi-circuit inductor and the opposite-phase primary or primaries of the second multi-circuit inductor being parts of the balancing circuit or circuits tuned either slightly above or below the receiver tuning; the primary of the first multi-circuit inductor being connected electrically with the preceding part of the adjacent signal-bearing circuit; and the secondary of the second multi-circuit inductor being connected electrically with the succeeding part of the adjacent signal-bearing circuit.

ALEXANDER GRAHAM ANDERSON.
